UNITED STATES PATENT OFFICE.

JOHN R. BLAKESLEE, JR., OF CLEVELAND, OHIO, ASSIGNOR TO THE AJAX MANUFACTURING COMPANY, OF CLEVELAND, OHIO, A CORPORATION OF OHIO.

BACK-STOP FOR FORGING-MACHINES.

943,377.

Specification of Letters Patent. Patented Dec. 14, 1909.

Application filed March 18, 1907. Serial No. 362,881.

To all whom it may concern:

Be it known that I, JOHN R. BLAKESLEE, Jr., a citizen of the United States, resident of Cleveland, county of Cuyahoga, and State 5 of Ohio, have invented a new and useful Improvement in Back-Stops for Forging-Machines, of which the following is a specification, the principle of the invention being herein explained and the best mode in 10 which I have contemplated applying that principle, so as to distinguish it from other inventions.

My invention relates to forging machines and the like, and has particular regard to 15 the provision of an improved back-stop for use in conjunction with machines of this class. As will be readily understood, it not infrequently becomes necessary in the forging of certain kinds of work, to provide 20 means for receiving and supporting the outer end of the piece being operated upon. This would be the case, for instance, in the forging of axles. As such supporting means are subjected to more or less thrust inci- 25 dentally to the stroke of the forming tool it is necessary to render the same quite rigid and substantial in construction. Heretofore this has been accomplished by connecting the stop member directly to the frame of 30 the machine, usually by lateral frame members secured to the sides of the machine frame and to those of the block serving as a stop, the latter being supported on the floor as most convenient. Two difficulties are at- 35 tendant upon this scheme of back-stop construction; first, adjustment of the stop in order to accommodate thereon stock of different lengths is not easy to arrange; and, second, by reason of the lateral frame mem- 40 bers the stop is made in effect a continuation of the forging machine and this not only takes up considerable unnecessary room, whether in use or not, but also renders the stock opening and dies of the machine in- 45 convenient of access. It has been with the view of obviating these and related difficulties that my present invention has been devised. Said invention, then, consists of the means hereinafter fully described and par- 50 ticularly pointed out in the claims.

The annexed drawings and the following description set forth in detail certain mechanism embodying the invention, such dis-

closed means constituting but one of various mechanical forms in which the principle of 55 the invention may be used.

In said annexed drawings: Figure 1, is a plan view of a forging machine with my improved back-stop construction connected therewith; Fig. 2 is a side elevation of the 60 same; Fig. 3 is a vertical transverse cross-section of the same shown on a larger scale and as taken on the line 3—3, Figs. 1 and 2; while Figs. 4 and 5 are respectively a plan view and a side elevation of a modified form 65 of rest designed for use with such stop under certain conditions of service.

In those figures of the foregoing list in which the forging machine appears, it should be stated that such machine is shown 70 in a partially dismantled condition for the reason that it is the relation of the back-stop thereto that is alone of present interest. Of such machine as shown then A designates the bed frame that is solidly mounted 75 upon a suitable foundation A' of concrete or the like. This bed frame A is formed with the usual longitudinal slide-way a for the reception of the block or cross-head, (not shown), that bears the forming tool, such 80 block being reciprocated by a suitable connecting rod joining the same with crank-shaft a' . The latter is driven, through intermediate gears a^2 , a^3 from drive shaft a^4 upon which is mounted the combined fly- 85 wheel and driving pulley a^5 . Opposite the end of slide-way a is formed the usual work-opening or slot a^6 through which the stock to be operated upon by the dies and forming tool of the machine is designed to be introduced. It is contiguous to this end of the machine, of course, that the back-stop, which forms the subject matter of the present application, is located. As a base for such stop a heavy bed-plate B is provided, such 90 bed-plate being embedded in the same concrete foundation A' upon which rests machine frame A. The forward end of the plate is for the sake of additional security and rigidity preferably attached to the base 95 of such machine frame as by bolts b . The upper face of bed-plate B, which from the disposition of the plate as aforesaid will be seen to lie substantially on a level with the base of the forging machine, forms a slide- 100 way upon which the back-stop proper is de-

signed to rest. Longitudinally disposed in such slide-way are provided two parallel under-cut grooves b' of inverted T cross-section, and intermediate of these grooves 5 is a series of holes or like recesses b^2 .

The back-stop proper consists primarily of a stand or post C resting as stated upon the slide-way formed by bed-plate B and having its front face c substantially perpendicular, its rear face supported by two spaced sloping abutments c' . Such stand or post is secured to the slide-way by bolts c^2 , the heads of which are held in undercut grooves b' . To further secure or retain the 10 stand in place, since the frictional contact between the base thereof and the slide-way would hardly suffice even with bolts c^2 drawn tight, a pin or plug c^3 that may be removably inserted in holes b^2 is employed. 15 As the position of the stand is from time to time changed pin c^3 is shifted from one hole b^2 to another and by the insertion of a suitable block or wedge c^4 is employed to back up solidly the stand against any thrust 20 on the latter's forward face. On this face, and near the base of the stand, is formed an integral outwardly projecting arm c^5 ; that portion of such face lying above arm c^5 is formed with a laterally projecting slide- 25 way provided with longitudinally disposed undercut grooves c^6 similar to those in the bed-plate B. Such face c , and hence the slide-way under consideration, is furthermore intersected for a portion of its length 30 by a longitudinally disposed slot c^7 . Vertically adjustable along this slide-way is a bracket C' that is secured thereto by being so formed as to embrace the laterally projecting portions thereof, and by means of 35 bolts c^8 , the heads of which are held in grooves c^6 . Adjustment of this bracket as to height is had by means of a rod c^9 having its lower end threaded in arm c^5 and its upper end disposed to support the bracket 40 on its under side. A portion of rod c^9 is suitably squared to receive a wrench; obviously by proper and sufficient rotation of the rod, the elevation of the bracket may be altered as desired. Slot c^7 is utilized to 45 receive a short, heavy bolt c^{10} having a circular head disposed to lie above bracket C' on slide-way c . The nut c^{11} of bolt c^{10} is designed to be inserted between the ribs or flanges, which the upper portions of 50 abutments c' terminate, and there be held against rotation. To loosen the bolt in the slot the head hence requires to be turned; to this end several radial apertures c^{12} are drilled in its periphery to receive a pin or 55 rod and thereby facilitate turning of the head. Such bolt is adjusted, in the manner just described, so as to lie with the head disposed adjacent to the end of a rest c^{13} , borne 60 by bracket C' and intended to receive and 65 sustain the outer end of the stock. This rest

consists simply of an oblong block having a longitudinal V-shaped groove or notch in its upper face.

In operation, the outer portion of the bar or other object being operated upon by the 70 forging machine is allowed to rest in this groove in block c^{13} , the end of such bar abutting directly against the head of bolt c^{10} . Adjustment of the latter, as also of bracket C', to thus receive and support the stock in 75 exactly the proper position to receive the stroke of the forming tool is easily made by the means and in the manner, previously explained. Endwise adjustment of the back-stop is of course effected by movement of the 80 stand C, as a whole, along slide-way B. Where final and more or less minute adjustment in this respect is required above that readily obtainable through plug c^3 and blocks c^4 , such adjustment may be had by inserting 85 one or more washers c^{14} between the head of bolt c^{10} and the face of the slide-way c . These washers are preferably of U-shape in order to permit of their insertion and removal without disengaging the bolt from the 90 slot.

Where, as in certain classes of work, the stock is much shorter than that for which the parts of the back-stop are shown as being arranged in Figs. 1 and 2, stand C may require to be moved up almost against the rear end of the forging machine. In this event it may be of advantage to employ the modified form of rest illustrated in Figs. 4 and 5. Such modified rest, like the regular rest, 100 consists of a block c^{15} , and differs therefrom mainly in being longer and having its forward end c^{16} shaped to fit snugly within work-opening a^6 of the machine frame. The upper face of the block is provided with a 105 groove or notch c^{17} as before.

The advantages arising from the improved construction of back-stop exemplified in the particular form thereof herein described should be sufficiently obvious not to require detailed explanation. Attention may, however, be called to the fact that the two difficulties, to which attention had earlier been directed, are here entirely overcome. Not only is no additional impediment interposed 110 to a close approach by the workmen to the machine when in operation, but when not in use, as will frequently be the case in connection with machines employed for general forging, the back-stop is out of the way or if desired may be removed entirely by simply loosening a few bolts. At the same time ready adjustment of such stop is to be had both longitudinally and vertically to exactly 115 position the stock for operation.

Other modes of applying the principle of my invention may be employed instead of the one explained, change being made as regards the mechanism herein disclosed provided the means stated by any one of the 120

following claims or the equivalent of such stated means be employed.

I therefore particularly point out and distinctly claim as my invention:

- 5 1. The combination with a forging machine or the like; of a slide-way terminally contiguous to the base of said machine, said slide-way lying substantially on a level with the floor on which said machine rests, and being supported by means disposed below said level; and a back-stop adjustably secured in said slide-way and projecting upwardly to the working level of said machine, the upper end of said back-stop being adapted to support the outer end of the stock being operated upon by said machine.
- 10 2. The combination with a forging machine or the like; of a back stop, comprising a stand having a substantially vertical front formed with a projecting arm, a slide-way thereabove and a longitudinally disposed slot intersecting such slide-way, a bracket mounted in said slide-way, means interposed between said arm and bracket for adjustably positioning the latter, a rest borne by said bracket, and a bolt secured in said slot and adapted to be secured with its head adjacent to said rest, said rest being adapted to support the outer end of the stock being operated upon and said head serving to retain said stock against end-wise movement.
- 15 3. A back-stop for forging machines or the like comprising a stand having a substantially vertical front formed with a projecting arm, a slide-way thereabove, and a longitudinally disposed slot intersecting said slide-way, a bracket mounted in said slide-way, a screw mounted in said arm and engaging said bracket to adjustably position the same, a rest borne by said bracket, and a bolt secured in said slot and adapted to be secured with its head adjacent to said rest, said rest being adapted to support the outer end of the stock being operated upon by said machine.
- 20 4. A back-stop for forging machines or the like comprising a stand having a substantially vertical front formed with a projecting arm, a slide-way thereabove and a longitudinally disposed slot intersecting such slide-way, a bracket mounted in said slide-way, means interposed between said arm and bracket for adjustably positioning the latter, a rest borne by said bracket, and a bolt secured in said slot and adapted to be secured with its head adjacent to said rest, said rest being adapted to support the outer end of the stock being operated upon and said head serving to retain such stock against end-wise movement.
- 25 5. The combination of a back-stop for forging machines or the like with a bed-plate, said bed-plate being formed with two parallel longitudinally disposed slots of T cross-section and with a series of holes lying intermediately of said slots, and said back-stop being mounted upon said bed-plate and projecting upwardly to the working level of the forging or like machine; bolts, with their heads secured in such T slots for securing said back-stop to said bed-plate, a pin in the rear of said back-stop adapted to engage said holes, respectively, to retain said stop in place, and means borne by said stop for supporting the outer end of the stock being operated upon by said machine, said supporting means being vertically adjustable and also longitudinally adjustable within a distance equal to the distance between adjacent holes in said bed-plate.
- 30 6. The combination of a back-stop for forging machines or the like with a bed-plate, said bed-plate being formed with two parallel longitudinally disposed slots of T cross-section and with a series of holes lying intermediately of said slots, and said back-stop being mounted upon said bed-plate and projecting upwardly to the working level of the forging or like machine; bolts, with their heads secured in such T slots for securing said back-stop to said bed-plate, a pin in the rear of said back-stop adapted to engage said holes, respectively, to retain said stop in place, and means borne by said stop for supporting the outer end of the stock being operated upon by said machine, said supporting means being vertically adjustable and also longitudinally adjustable within a distance equal to the distance between adjacent holes in said bed-plate.
- 35 7. The combination of a back-stop for forging machines or the like with a bed-plate, said bed-plate being formed with two parallel longitudinally disposed slots of T cross-section and with a series of holes lying intermediately of said slots, and said back-stop being mounted upon said bed-plate and projecting upwardly to the working level of the forging or like machine; bolts, with their heads secured in such T slots for securing said back-stop to said bed-plate, a pin in the rear of said back-stop adapted to engage said holes, respectively, to retain said stop in place, and means borne by said stop for supporting the outer end of the stock being operated upon by said machine, said supporting means being vertically adjustable and also longitudinally adjustable within a distance equal to the distance between adjacent holes in said bed-plate.
- 40 8. The combination of a back-stop for forging machines or the like with a bed-plate, said bed-plate being formed with two parallel longitudinally disposed slots of T cross-section and with a series of holes lying intermediately of said slots, and said back-stop being mounted upon said bed-plate and projecting upwardly to the working level of the forging or like machine; bolts, with their heads secured in such T slots for securing said back-stop to said bed-plate, a pin in the rear of said back-stop adapted to engage said holes, respectively, to retain said stop in place, and means borne by said stop for supporting the outer end of the stock being operated upon by said machine, said supporting means being vertically adjustable and also longitudinally adjustable within a distance equal to the distance between adjacent holes in said bed-plate.

outer end of the stock being operated upon and said head serving to retain such stock against end-wise movement.

4. A back-stop for forging machines or the like comprising a stand having a substantially vertical front formed with a projecting arm, a slide-way thereabove, and a longitudinally disposed slot of T cross-section intersecting said slide-way, a bracket mounted in said slide-way, a screw mounted in said arm and engaging said bracket to adjustably position the same, a rest borne by said bracket, and a bolt having its nut secured in said slot and its head disposed adjacent to said rest, said rest being adapted to support the outer end of the stock being operated upon and said head serving to retain such stock against end-wise movement.

5. The combination of a back-stop for forging machines or the like with a bed-plate, said bed-plate being formed with two parallel longitudinally disposed slots of T cross-section and with a series of holes lying intermediately of said slots, and said back-stop being mounted upon said bed-plate and projecting upwardly to the working level of the forging or like machine; bolts, with their heads secured in such T slots for securing said back-stop to said bed-plate, a pin in the rear of said back-stop adapted to engage said holes, respectively, to retain said stop in place, and means borne by said stop for supporting the outer end of the stock being operated upon by said machine, said supporting means being vertically adjustable and also longitudinally adjustable within a distance equal to the distance between adjacent holes in said bed-plate.

Signed by me, this 12th day of March, 1907.

JOHN R. BLAKESLEE, JR.
